Lloyd L. Huddleston,

BY *F. G. Fischer,*

ATTORNEY.

UNITED STATES PATENT OFFICE.

LOYD L. HUDDLESTON, OF KANSAS CITY, MISSOURI.

BURGLAR-PROOF SASH-LOCK.

1,353,533.

Specification of Letters Patent. Patented Sept. 21, 1920.

Application filed December 19, 1919. Serial No. 346,116.

To all whom it may concern:

Be it known that I, LOYD L. HUDDLESTON, a citizen of the United States, residing at Kansas City, in the county of Jackson and 5 State of Missouri, have invented certain new and useful Improvements in Burglar-Proof Sash-Locks, of which the following is a specification.

My invention relates to improvements in 10 burglar-proof sash locks and my objects are to produce a simple and inexpensive device of this character whereby the upper and lower sashes of a window may be locked in closed position, or in a partly open position 15 for the purpose of ventilation.

A further object is to provide a device which can be readily applied to the window sashes without defacing the same any more than is done by inserting a few screws and 20 when applied and in operation will prevent anyone on the outside from opening the sashes far enough to gain access to the interior of the building without breaking the window glass.

25 In order that the invention may be fully understood, reference will now be had to the accompanying drawing, in which:

Figure 1 is a front elevation of a portion 30 of the upper and lower sashes of a window locked together in a partly open position.

Fig. 2 is a vertical section on line II-II of Fig. 1.

Fig. 3 is a horizontal section of the sash lock.

35 Fig. 4 is a vertical cross section of the sash lock.

A, represents the upper sash and B the lower sash of a window frame C. A stile a of the upper sash is provided with a plate 2 secured to said stile by suitable means 40 such as screws 4. The plate 2 is provided with a vertical series of holes 6 to receive the forward end of the bolt 8 of the sash lock 10.

45 The bolt 8 is reciprocably mounted in a barrel 12, provided at its base with marginal flanges 14 having holes 16 through which screws may pass to secure said barrel 12 to the upper surface of lower sash B. 50 The bolt 10 has a longitudinal recess 16^a in one side forming front and rear shoulders 18 and 20, respectively. The recessed side of the bolt 8 has a series of rack teeth 22

for engagement with a pinion 24 provided at its upper and lower portions with journals 26 and 28, respectively, which latter extends through the bottom 30 of the barrel 12.

The journal 26 is provided with a circular flange 32 bearing on top of the barrel 12, 60 while the journal 28 is peened or riveted as indicated at 34 and coacts with the flange 32 in holding the bottom 30 and the barrel 12 together. The flange 32 is surmounted by a knob 36, whereby the pinion 24 may 65 be rotated in one direction to throw the bolt 8 outwardly into one of the holes 6 of the plate 2, or inwardly to move said bolt 8 out of said hole 6.

Before the sash lock is applied to the top 70 of the sash B, the bolt 8 is prevented from falling out of the barrel 12 by the shoulder 20 contacting the pinion 24, which latter, however, is designed to work with sufficient friction to prevent accidental rotation there- 75 of and consequent movement of the bolt 8 either outwardly or inwardly.

In practice the lock 10 is secured to the top of the sash B in such position that the bolt 8 may enter any of the holes 6 of the 80 plate 2 when the sash A is adjusted to bring any one of said holes 6 in axial alinement with the bolt 8. If it is desired to lock the sashes in closed position, they are adjusted to bring the lowermost hole 6 in position 85 to admit the forward end of the bolt 8, which is shot into said hole by proper manipulation of the knob 36 and the pinion 24. If the sashes are to be locked in a partly open position to admit of ventilation, 90 they are adjusted to bring one of the intermediate holes or the uppermost hole 6 in position to admit the bolt 8. When it is desired to leave the sashes free to open fully, the bolt 8 is drawn backwardly 95 against the rear wall of the barrel 12, as indicated on Fig. 3.

From the foregoing description, it is apparent that I have produced a sash lock embodying the advantages above pointed out, 100 and while I have shown and described the preferred form of my invention, I reserve the right to make such changes in the construction, proportion and arrangement of parts as properly fall within the spirit and 105 scope of the claim.

Having thus described my invention, what I claim and desire to secure by Letters Patent, is:

In a sash lock, a barrel having a separate bottom portion and flanges to rest on top of a window sash to which said flanges may be secured by suitable means such as screws, a pinion, journals at the ends of said pinion and rotatably mounted in the barrel, a bolt 5 having a longitudinal recess with rack teeth to intermesh with the pinion, a circular shoulder on one of the journals and overlapping the barrel to coact with the other

journal in holding the pinion in position, a knob on said circular flange to rotate the 15 same and cause the pinion to throw the bolt in and out, and a shoulder on the bolt to engage the pinion and limit the outward movement of said bolt.

In testimony whereof I affix my signature, 20 in the presence of two witnesses.

LOYD L. HUDDLESTON.
